UNITED STATES PATENT OFFICE.

GEORGE O. DRAPER, OF HOPEDALE, MASSACHUSETTS, ASSIGNOR TO THE DRAPER COMPANY, OF SAME PLACE AND PORTLAND, MAINE.

LOOM.

SPECIFICATION forming part of Letters Patent No. 596,487, dated January 4, 1898.

Application filed June 1, 1897. Serial No. 638,874. (No model.)

To all whom it may concern:

Be it known that I, GEORGE O. DRAPER, of Hopedale, county of Worcester, State of Massachusetts, have invented an Improvement in 5 Looms, of which the following description, in connection with the accompanying drawings, is a specification, like letters and figures on the drawings representing like parts.

In looms for weaving it usually happens 10 that when the filling is exhausted from the filling-carrier the loose end of filling will be carried by the shuttle into the shed and left in the cloth between the selvages, leaving an imperfection in the cloth. Means have been 15 devised heretofore to detect or feel the filling on the filling-carrier in the shuttle and to operate through suitable devices to either automatically stop the loom when the filling has been nearly exhausted or exhausted to a pre- 20 determined extent or to supply a fresh supply of filling at such time, the feeler acting through the open top of the shuttle to engage or detect the filling on the filling-carrier.

In my present invention I mount the feeler 25 in such position that it enters the shuttle through a slot in the side wall thereof, and by a system of multiplying mechanism a very minute movement of the feeler will effect a considerable movement of a bunter adapted 30 to coöperate with and actuate suitable mechanism to either stop the loom or change the filling just before it is exhausted from the filling-carrier in the shuttle.

Various other features of my invention will 35 be hereinafter described in the specification and particularly pointed out in the claims.

Figure 1 is a top or plan view of a sufficient portion of a loom to be understood with my invention applied thereto, one end of the lay 40 with the shuttle-box and shuttle therein being shown, the various parts being in the position assumed when the filling-carrier is well supplied with filling, the filling-changing mechanism being omitted. Fig. 2 is a trans- 45 verse sectional view thereof on the line $x-x$, Fig. 1, the filling-changing mechanism being shown. Fig. 3 is a top or plan view of the feeler and coöoperating parts when the lay is fully forward, with the feeler withdrawn from 50 the path of the shuttle. Fig. 4 is a plan view similar to Fig. 1, but with the filling exhausted

sufficiently to cause the operation of the feeler to effect the change of filling. Fig. 5 is an enlarged detail view of the adjustable tip or end of the feeler, and Fig. 6 is a modification 55 to be referred to.

The lay A, shuttle-box A', and the breast-beam A^x are and may be of usual or well-known construction in looms, the filling-changing mechanism (shown in Fig. 2) comprising a rotatable filling-feeder, only one member *a* being shown. The stud *f*, the pusher *f'*, mounted thereon and having the depending end *f*³ and a projection 21, the spring 22 to raise the pusher, and the arm *f*⁶ on the stud 60 *f*, having pivotally mounted upon it a tip supporting or directing device *f*⁸, are and may be all as represented in United States Patent No. 529,942, wherein like letters and figures are used herein to designate like parts, the operation of the pusher to transfer a fresh filling-carrier to the shuttle S being well understood. A bracket *b*, suitably attached to the front side 65 of the lay, is provided with an upright stud *b*', on which is pivotally mounted a lever *b*²*b*³, the 70 longer arm *b*², constituting a feeler-carrier, having a curved slot *b*⁴ therein with the stud as its center. The shorter arm *b*² of the lever is bent rearwardly to enter at times a slot 30 in the front wall of the shuttle-box A', the tip 75 or extremity of the said arm, which constitutes the feeler, being preferably made adjustable, as best shown in Fig. 5. Referring to said Fig. 5, the end of the arm is laterally shouldered at 2 and longitudinally grooved 80 at 3 to receive therein and guide a pin 4 on the shank 5 of a tip 6, having a preferably rounded end, adjustably held in place by a screw 10, rotation of the latter moving the tip in or out to vary the effective length of the 85 feeler.

The feeler and its carrier are so mounted on the lay relatively to the shuttle-box that when the carrier is swung on its fulcrum the tip of the feeler will enter the slot 30 in the 90 shuttle-box, passing through a slot *s*^x in the side wall of the shuttle when properly positioned in the box and engaging the filling on the filling-carrier *c*, as in Fig. 1.

A spring *s*, connected with the feeler, normally tends to move the tip 6 thereof into the shuttle-box, and the end of the carrier *b*³ 100

is engaged by the breast-beam A^x or some other suitable fixed part of the loom as the lay is about completing its forward stroke, rocking the feeler against the action of its 5 spring s and withdrawing it from the path of the shuttle, as in Fig. 3, the feeler being retained in such position during a portion of the backward stroke of the lay by a spring-latch l , mounted on the bracket b . Such 10 withdrawal of the feeler from the path of the shuttle permits the latter to be thrown across the lay at the next pick.

I have herein shown a bunter d , pivotally mounted on the stud b' and adapted to be 15 moved into or out of the path of a dog d' , carried by the end f^x of the pusher, said bunter being connected by a link d^2 with one arm of a bell-crank lever d^x , fulcrumed at d^3 on the bracket b near the slotted end of the feeler- 20 lever. A stud or pin d^4 on the other arm of the bell-crank lever d^x enters the slot b^4 of the feeler-carrier, and when the latter is swung outward, as in Fig. 4, far enough to bring the 25 end 12 of said slot against stud d^4 the lever d^x will be rocked to swing the bunter d into full-line position, Fig. 4. The bunter is also 30 acted upon by a spring s' , mounted on the feeler near its fulcrum, said spring from its position being normally relaxed and inoper- 35 ative; but when the feeler is moved outwardly by engagement of the breast-beam and feeler-carrier, as in Fig. 3, the spring is compressed gradually and sufficient energy stored up 40 therein to return the bunter and attached parts to normal position after engagement 45 of the bunter and dog.

A flexible connection or cord l' is fastened at one end to the loom-frame A^5 and at its other end to the latch l , passing over an intermediate idler pulley or sheave l^2 on the lay, the connection l' being of such length that it will not be tightened until the lay has 40 nearly completed its backward stroke and after the shuttle has been thrown, tightening 45 of the said connection, withdrawing the latch l from engagement with and releasing the feeler-carrier. When so released, the feeler-controlling spring s acts to move the feeler through the slot s^x in the shuttle if the latter 50 is in the shuttle-box, so that its tip may feel or engage the filling c^x on the filling-carrier c , as in Fig. 1, and until the filling is exhausted to a predetermined extent the end 12 of the slot b^4 will not engage the stud d^4 upon 55 such release and movement of the feeler and its carrier.

The lay moves forward after release of the feeler, and as the bunter d is in inoperative position it will not engage the dog d' , and the 60 filling-changing or other mechanism controlled thereby will not be operated. When the lay beats up, the feeler-carrier b^2 will be rocked by engagement with the breast-beam, as described, to withdraw the feeler from the 65 shuttle, and the carrier will be locked by the latch l , as in Fig. 3. At the same time the end 12 of the slot b^4 moves back from the pin

d^4 , and the compressed spring s' acts to move the bunter into inoperative position, Figs. 1 and 3. On the next beat up of the lay the shuttle will be in the opposite shuttle-box, and after its release, as described, the feeler will move into the now empty shuttle-box A' , and it will swing in to its full extent, (see dotted lines, Fig 4,) the end 12 of the slot b^4 then 70 acting on the pin d^4 to rock the bell-crank lever d^x and throw the bunter d to the right in dotted lines, Fig. 4, and out of the path of the dog d' , so that the mechanism controlled by the dog will not be operated. As the lay then 75 beats up, the feeler-carrier will be swung in by engagement with the breast-beam, as described, compressing the bunter-controlling spring s' , and as soon as the lay moves back far enough to permit the bunter to swing on its pivot past the dog the bunter-spring s' will 80 act to restore the parts to normal position, (Shown in Fig. 1.) This arrangement and operation obviate the use of mechanism operative at every alternate pick to prevent operation of the filling-changing mechanism- 85 and as the latter mechanism is at the same side of the loom as the feeler and the controlling devices therefor all intermediate devices between the loom sides are done away 90 with.

Let it now be supposed that the feeler is desired to operate the filling-changing mechanism or, it may be, stopping mechanism for the loom when the filling has been drawn off until the shank or straight portion of the filling-carrier c is bared or covered only by a few turns of filling. At such time when the lay beats up and the shuttle is in the shuttle-box adjacent the feeler the latter will have a greater amplitude of movement, as in full lines, Fig. 4, than when more filling is present. This greater movement of the feeler and its carrier brings the end 12 of the slot b^4 into 105 engagement with the pin d^4 of the bell-crank lever, rocking the latter to bring the bunter d directly into operative position in front of the dog d' , so that as the lay completes its 110 forward stroke the dog will be moved by the bunter to actuate the pusher and transfer a 115 fresh filling-carrier from the filling-feeder to the shuttle.

The operative position of the bunter is shown in full lines, Fig. 4, and it will be observed that while the feeler-carrier will be 120 engaged and moved somewhat by the breast-beam before engagement of the dog and bunter the bunter-spring will not be compressed sufficiently to throw the bunter to the left before it engages the dog.

After the mechanism controlled by the dog has operated either to stop the loom or to transfer a fresh filling-carrier to the shuttle the lay moves back, and as soon as the bunter and dog are disengaged the bunter-spring s' 130 will restore the bunter and its connected devices to normal position, Fig. 1 or 3, it being remembered that at each forward beat of the lay the feeler-carrier and feeler will be rocked

or swung to withdraw the feeler from the path of the shuttle and that the feeler will be locked in such position until on the backward stroke of the lay the next shot of the shuttle has been made.

It will be obvious that instead of the slot b^4 herein shown in the feeler-carrier a notch therein would fulfil all the functions of the slot, such construction being shown in Fig. 6, wherein the feeler-carrier b^{30} is provided with an open-sided notch b^{40} .

The feeler mechanism operates at every stroke of the lay whether the shuttle is in the adjacent shuttle-box or in the shuttle-box at the other end of the lay.

By the system of lever-arms herein shown a very slight movement of the feeler operates to give a very considerable movement to the bunter.

20 By means of the adjustable tip 6 on the feeler the mechanism can be regulated with the very greatest nicety to act when practically any desired number of turns or layers of filling remain on the filling-carrier, or the

25 mechanism may be adjusted thereby to operate when the filling has been drawn off sufficiently to leave the shank of the filling-carrier bare. Referring to Fig. 4, where such latter condition of affairs is shown, if it be

30 desired to operate the dog-controlled mechanism when a portion of the filling yet remains on the shank of the filling-carrier the adjusting-screw 10 would be turned to draw the tip in sufficiently to compensate for the 35 thickness of the filling, and thereby the feeler-carrier and feeler as a whole would have the same throw.

In my invention the feeler performs a double function—viz., to feel or detect the filling on the filling-carrier in the shuttle and to act as a shuttle-positioning device when used with a filling-changing mechanism. In

40 such case the slot in the shuttle-wall will be so proportioned that if the shuttle is far out of position in the shuttle-box the feeler cannot enter the slot, but will strike the wood of the shuttle. The feeler-actuating spring 8 of course permits such stoppage of the feeler, and consequently the feeler-carrier will not

45 be moved far enough to operate the bunter and through it effect the actuation of the filling-changing mechanism. It is thus obvious that there is no danger of a filling-carrier being transferred from the filling-changing mechanism when the shuttle is not properly positioned to receive it to thereby cause breakage.

Having described my invention, what I claim, and desire to secure by Letters Patent, 50 is—

1. In a loom, the combination with a shuttle containing a filling-carrier and having a slotted side, of a feeler mounted independently of the shuttle, and means to move said feeler in a lateral plane to enter the slot in the shuttle and coöperate with the filling, substantially as described.

2. In a loom, the combination with a shuttle containing a filling-carrier and having a slotted side, of a feeler mounted independently of the shuttle, means to move said feeler in a lateral plane to enter the slot in the shuttle and coöperate with the filling, and filling-changing mechanism controlled by said feeler and at the same side of the loom, to operate upon exhaustion of the filling to a predetermined extent, substantially as described.

3. In a loom, the combination with a shuttle containing a filling-carrier and having a slotted side, of a feeler mounted independently of the shuttle, means to move said feeler in a lateral plane to enter the slot in the shuttle and coöperate with the filling, filling-changing mechanism controlled by said feeler and at the same side of the loom, to operate upon exhaustion of the filling to a predetermined extent, and multiplying connections intermediate the feeler and said mechanism, to operate substantially as described.

4. In a loom, the combination with the lay having a shuttle-box, and a feeler mounted on the lay, of means to move said feeler to enter the shuttle-box at each beat of the lay, independent means to withdraw the feeler from the shuttle-box as the lay beats up, and a detent to retain the feeler inoperative during a portion of the back stroke of the lay, substantially as described.

5. In a loom, the combination with the lay having a shuttle-box, a shuttle containing a filling-carrier and having a slot in its side, and a feeler mounted independently of the shuttle, of means to move the feeler to enter the slot of the shuttle and coöperate with the filling, means to withdraw the feeler from the path of the shuttle, a device to retain the feeler inoperative until after the next shot of the shuttle, and means to automatically release the feeler, substantially as described.

6. In a loom, the combination with the lay, a shuttle containing a filling-carrier, and a feeler mounted independently of the shuttle, of means to move the feeler to coöperate with the filling, and an adjustable tip for the feeler, substantially as described.

7. In a loom, the combination with the lay, a shuttle containing a filling-carrier, and a feeler mounted independently of the shuttle, of means to move the feeler at predetermined intervals to coöperate with the filling, means to positively lock the feeler in inoperative and retracted position while the shuttle is thrown through the shed, a device to release the feeler after the shuttle has completed its throw, and filling-changing mechanism controlled by the feeler, to operate when the filling in the shuttle is exhausted to a predetermined extent, substantially as described.

8. In a loom, the lay, a shuttle containing a filling-carrier, and a feeler mounted on the lay, combined with means to move the feeler to coöperate with the filling, filling-changing mechanism, an actuating-bunter therefor, connections between said bunter and feeler,

to move the latter into operative position when the filling is exhausted to a predetermined extent, and independent means controlled by the feeler to return the bunter to 5 normal, inoperative position, substantially as described.

9. In a loom, the combination with a shuttle containing a filling-carrier, a feeler mounted independently of the shuttle, and a feeler-carrier, of means to swing said feeler-carrier to effect coöperation of the feeler with the filling, a bunter, multiplying connections between it and the feeler, whereby a slight movement of the latter will cause an increased 15 movement of the bunter, and filling-changing mechanism actuated by the bunter when the filling is exhausted to a predetermined extent, substantially as described.

10. In a loom, the lay, a shuttle-box, a shuttle containing a supply of filling, and a feeler to coöperate with and determine the amount of filling when the shuttle is in the shuttle-box, combined with means to move the feeler toward the filling, independent means to retract it, filling-changing mechanism controlled by the feeler, a detent to retain the feeler inoperative when the shuttle is in motion, and means to release the feeler after the shuttle has completed its throw, substantially 30 as described.

11. In a loom, a feeler to detect the exhaustion of filling in the shuttle to a predetermined extent, means to move the feeler into operative position, independent means to retract it, and a detent to retain the feeler stationary and in retracted position during a portion of the stroke of the lay, substantially as described.

12. In a loom, a shuttle having a slot in 40 one of its vertical side walls, a feeler independent of the shuttle and adapted to detect the exhaustion of filling in the latter, a vertical pivot upon which the feeler is mounted, and means to move said feeler in a substantially horizontal plane.

13. In a loom, filling-changing mechanism, a shuttle having a slot in its side and a co-operating feeler to control said filling-changing mechanism, said slot permitting the effective movement of the feeler only when the 50 shuttle is in proper position to receive a supply of filling, substantially as described.

14. In a loom, filling-changing mechanism coöperating with one shuttle-box on the lay, combined with a shuttle, and a feeler to detect the volume of filling on the filling-carrier in the shuttle when the latter is in the shuttle-box in which it shall receive a fresh supply of filling at the time indicated by said feeler, substantially as described. 60

15. In a loom, the combination with a shuttle containing a filling-carrier, of a feeler, means to move it to detect the position of the shuttle in the shuttle-box and to coöperate with the filling when the shuttle is properly 65 positioned, and filling-changing mechanism controlled by the feeler, substantially as described.

16. In a loom, the combination with a shuttle containing a filling-carrier and having a 70 slotted side, of a combined filling-feeler and shuttle-position - detecting device, means to move the same to enter the slot of the shuttle and coöperate with the filling when the shuttle is properly positioned in the shuttle-box, 75 and filling-changing mechanism controlled by the said feeler, the shuttle when improperly positioned in the box preventing movement of the feeler sufficient to effect operation of the filling-changing mechanism, substantially as described. 80

In testimony whereof I have signed my name to this specification in the presence of two subscribing witnesses.
